EDGE FASTENING FOR TABLE TOP
COVERINGS

Glenn H. Norquist, Jamestown, N. Y.

Application June 27, 1950, Serial No. 170,642

6 Claims. (Cl. 311—106)

1

This invention relates to edge fastening for table top coverings and more particularly to table tops having a covering sheet whose peripheral edges are impressed into a groove formed in the edging frame which is then closed by a decorative spline inserted therein.

Covered table tops having a covering sheet applied to a substantial area of the table top are in substantial demand as bridge tables, game tables, living room tables and recreation room tables. While such tables may be constructed in numerous shapes and designs, and may be equipped with either folding legs or permanently fixed legs, they are generally characterized by an edging frame made from selected finished hard-woods which provide an attractive edging border for the table top. The covering sheet is stretched over the center section of the table top and extends to a decorative spline set into the finished face of the edging frame to provide a trim and attractive border for the periphery of the stretched covering. Covering sheets for table tops are made of various materials which may be selectively employed, such as natural leathers, artificially simulated leathers, coated fabrics and various resinous or plastic sheetings of the required toughness and wearability.

It has been common practice to secure the peripheral edge portion of the covering sheet to the edging frame by cutting a groove in the edging frame, then inserting the peripheral edge portion of the covering sheet into the groove, and then closing the mouth of the groove by a trimming spline made from a suitable hard plastic material which is wedged into the groove in a manner intended to lock the peripheral edge portion of the covering sheet therein. The covering sheet, the trimming spline, and the finished surface of the edging frame may be made in selected colors to emphasize artistic color contrasts, color harmonies, and color variations which are particularly appealing and restful to the eyes of the user.

A serious drawback in covered table tops as presently constructed arises from the difficulty encountered in securely and permanently locking the peripheral edge portion of the covering sheet in the groove of the edging frame so that the peripheral edge portion will not become loosened from the groove during use, or for reasons of rough handling, or as a result of temperature or humidity changes. This difficulty of adequately locking the peripheral edge portion of the covering sheet in the receiving groove becomes even more seriously acute when plastic sheetings are

2

used as the covering material, since plastic covering sheets commonly used have a tendency to slip and creep. While the trimming spline as formed from hard plastic material adequately serves to close the groove and additionally provides a trimmed edge for the sheet covering, it has heretofore been expected that the trimming spline would also serve as a wedging element to wedge the peripheral edge portion of the covering sheet in the margin forming groove. Such plastic trimming splines, while providing a satisfactory decorative trim for the marginal edge of the covering sheet, have been found to be inadequate to permanently lock the peripheral edge portion of the covering sheet in the receiving groove, with the result that the sheet covering often loosens from the table top, causing wrinkling of the center section thereof in a manner to materially detract from the intended finished appearance of the table top.

In accordance with this invention, improved means are provided for securely and permanently locking the peripheral edge portion of the covering sheet within the receiving groove formed in the table top edging frame so that the covering sheet will maintain its taut and stretched appearance, with the trimming spline permanently and immovably locked in the receiving groove, thereby overcoming the serious drawbacks to covered table tops as heretofore constructed. The improved locking means comprises a rattan strip inserted into the groove in a manner to bind and lock the peripheral edge portion of the covering sheet firmly and permanently in the groove.

The rattan strip is initially substantially circular in cross section, and has a diameter closely approaching the width of the groove. As the normally round rattan strip is pressure driven into the groove by the pressure roller, the rattan strip is pressure shaped into generally rectangular form, with the side faces thereof flattened against the groove inserted inner and outer side sections of the covering sheet, which are thereby correspondingly pressed against the roughened inner and outer vertical faces of the groove. The bottom face of the rattan strip is thus flattened, will also flatten out the bottom section of the covering sheet against the flat bottom face of the groove and firmly wedge the corners of the covering sheet into the bottom corners of the groove. The flattened rattan strip frictionally grips and securely wedges the peripheral edge portion of the covering sheet into compressed, hugging conformity against the flat side and bottom faces of the groove, thus serving to permanently lock

the peripheral edge portion of the covered sheet therein.

The plastic trimming spline is then pressure wedged into the groove to provide a closure therefor. As thus constructed, the trimming spline is relieved of the upward pressure which would otherwise be exerted against the bottom face of the spline by the groove depressed edge portion of the covering sheet, because the underlying rattan strip has the capacity to firmly resist the upward pressure exerted thereon by the groove depressed portion of the covering strip, and remains immovably locked therein.

Covered table tops may be constructed in accordance with this invention without appreciably adding to the cost thereof over the cost of covered table tops as heretofore constructed. These improved covered table tops maintain their finished appearance through a lifetime of use, with the covering sheet remaining stretched and taut at all times irrespective of changes in temperature or humidity conditions.

Other objects and advantages of this invention will become apparent as the disclosure proceeds.

Although the characteristic features of this invention will be particularly pointed out in the claims, the invention itself, and the manner in which it may be carried out, may be better understood by referring to the following description taken in connection with the accompanying drawings forming a part hereof, in which

Fig. 1 is a fragmentary perspective view of a covered table top having the improved means for locking the peripheral edge portion of the covering sheet in fixed position to the edging frame.

Fig. 2 is a fragmentary vertical cross-sectional view of the table top showing the covering sheet in process of being applied thereto.

Fig. 3 is an enlarged fragmentary cross-sectional detail showing a portion of the edging frame and the receiving groove therein, this view showing the round rattan strip in position to be pressed into the frame groove.

Fig. 4 is a fragmentary cross-sectional detail of the edging frame showing the peripheral edge portion on the covering sheet as initially forced into the groove by the rattan strip which then becomes pressure deformed into generally elliptical shape as indicated.

Fig. 5 is another enlarged fragmentary cross-sectional detail showing a portion of the edging frame and its receiving groove, this view showing the covering sheet at a further stage of assembly and wherein the trimming spline has been partially forced into the groove and pressed against the underlying rattan strip to thereby further reshape the rattan strip so that its cross section approaches rectangular form.

Fig. 6 is a further enlarged fragmentary cross-sectional detail of the edging frame as the same appears when the covering sheet has been fully applied to the table top, with the peripheral edge portion thereof locked in the groove of the edging frame by the fully compressed rattan strip and trimming spline wedged therein, the resultant tail portion of the covering sheet being trimmed off and removed.

Fig. 7 is another fragmentary cross-sectional detail of the edging frame showing the peripheral edge portion of the covering sheet as finally forced into the groove by roller pressure exerted on the rattan strip causing reshaping of the rattan strip into substantial rectangular form.

Fig. 8 is a fragmentary cross-sectional detail of the grooved portion of the edging frame showing an alternative modification wherein the terminus end portion of the covering sheet has been severed to provide an end section which is folded over the flat upper face of the pressure shaped rattan strip.

Fig. 9 is a fragmentary cross-sectional detail of the grooved portion of the edging frame showing a trimming spline in process of being pressure wedged into the mouth of the groove illustrated in Fig. 8.

Fig. 10 is a fragmentary cross-sectional detail of the edging frame as the same would appear when the trimming spline has been pressure wedged into final position within the groove with the bottom face of the spline seating against the underlying end section of the covering sheet.

Fig. 11 is a fragmentary cross-sectional detail of the edging frame showing a trimming spline in process of forcing the peripheral edge portion of the covering sheet into the groove as heretofore practiced, and which procedure causes the covering sheet to bind against the upper corners of the groove with resultant thinning deformation of the side sections of the covering sheet which line the side faces of the groove; and

Fig. 12 is a fragmentary cross-sectional detail of the edging frame showing the trimming spline as finally driven into the groove in accordance with prior art practice, this view showing the side and bottom sections of the covering sheet lining the groove under such substantial tension as to exert considerable lifting pressure on the groove inserted trimming spline.

Similar reference characters refer to similar parts throughout the several views of the drawing and the specification.

There is shown in Fig. 1 for purposes illustration, a perspective view of a typical table top to which the covering sheet has been applied, with its peripheral edge portion secured thereto by the improved locking means of this invention. While this improved locking means may be used to secure a covering sheet to table tops which are generally rectangular or any other desired shape, a table top is shown in Figs. 1 and 2 for purposes of illustration having a generally round or elliptical contour presenting an arcuate shaped apron frame 1 which may be built up from plywood presenting a finished veneer sheet 1' on the exterior thereof. The table top edging frame 2 may be formed from either straight or arcuate shaped sections whose abutting ends are glued together to present substantially invisible joints. The table top edging frame 2 is usually made from selected hardwood and is finished to present a finished outer edge 4 and a flat top surface 5 which can be stained and lacquered or otherwise coated to present a finished table top surface.

A table top panel 6 has the peripheral edge thereof seated within a groove 7 formed in the inner edge of the table top edging frame 2 so as to be supported by an underslung shelf portion 8 forming a part of the edging frame 2. The table top panel 6 may be formed from laminated plywood of sufficient thickness to provide adequate strength, and its peripheral edge may be supported by and glued to the shelf portion 8 of the edging frame 2 to provide a rigid table top structure. The upper face 9 of the table top panel 6 should be smooth and flat so as to extend in the same flat plane as the top surface 5 of the edging frame 2, but need be given no special

finish since it is to be covered by the table top covering sheet 20.

A generally rectangular shaped groove 10 of generally rectangular cross-section is cut into the upper surface 5 of the edging frame to receive the peripheral edge portion of the covering sheet 20. The groove 10 is usually made approximately $\frac{1}{8}$ of an inch in width and approximately $\frac{1}{4}$ to $\frac{1}{8}$ of an inch in depth, and may be selectively located in the upper surface 5 of the table edging frame 2 to leave uncovered the desired area 5 of the edging frame 2, leaving a selected marginal surface area 5' to be covered. The groove 10 may present straight runs which meet in relatively square corners as would be the case when covering a rectangular shaped table top, or the groove 10 may present a continuous circular or elliptical run as would be the case in covering a round or generally elliptical shaped table top as indicated in Figs. 1 and 2.

The groove 10 may be cut by a circular saw blade suitably guided to properly locate the groove and to form a groove of the proper depth. As thus formed, the groove 10 presents a somewhat roughened inner side face 11 and a roughened outer side face 12 which are substantially parallel, and a roughened bottom face 13 which is substantially parallel with the finished face 5 of the edging frame. As indicated in Figs. 3, 4 and 5, the sawed groove 10 presents a relatively sharply defined upper inner corner 14, a sharply defined upper outer corner 15, and sharply defined bottom corners 16. The roughened side faces 11 and 12 and the roughened bottom face 13 of the sawed groove 10 present frictional surfaces which assist in retaining the peripheral edge portion of the covering sheet 20 securely locked in its final inserted position within the groove 10.

The table covering sheet 20 may be formed from natural or artificially simulated leathers, suitably coated textile fabrics, or selected plastic sheeting of various types, as commonly used for table covering purposes. The materials from which such covering sheets 20 are made have substantial strength and wearability, and the better grades thereof are substantially resistant to heat, and will not easily burn or deteriorate under normal usage. Table covering sheets commonly employed also have a stretch characteristic when subjected to a tensile pull, but will tend to contract to its original form and size to the extent that the tensile pull is released. Such table covering sheets are usually made in various selected colors so that color harmony and color contrast effects may be achieved between the covering sheet 20, the trimming spline 35, and the finished surface 5 of the edging frame 2.

In accordance with this invention, the peripheral edge portion of the covering sheet is firmly and immovably secured in the receiving groove of the table edging frame in a manner to resist slippage or creepage of the edge portion for whatever cause, by the use of a rattan strip 30, which initially is substantially circular in section and whose diameter is approximately equal to the width of the groove 10 into which it is to be inserted as indicated in Fig. 3. In applying the covering sheet 20 to the table top, the covering sheet is cut to the approximate shape of, but to a size somewhat in excess of, that required for covering purposes. The covering sheet 20 is spread over the table top with the center section 21 covering the table top panel 6, and with the peripheral edge portion thereof ex-

tending over the frame groove 10. The rattan strip 30 is then placed over that portion of the covering sheet 20 which spans the groove 10 as shown in Fig. 3, and substantial downward pressure a , as indicated at the right hand side of Fig. 2, is then applied to the rattan strip.

A pressure roller of narrow width so that it will snugly sink into the groove may be rolled over the rattan strip 30 to thereby drive it into the groove. The rattan strip 30 is originally of such diameter that when it is forced into the groove 10 by the pressure roller, it assumes a generally elliptical shape as indicated in Fig. 4, with the side faces 21 thereof substantially flattened. When the rattan strip 30 has thus been driven to the bottom of the groove 10, the peripheral edge portion of the covering sheet is drawn into the groove 10 without substantial distortion of the covering sheet, and so that the center section 21 of the covering sheet 20 will be drawn to lie flat and smooth against the top face 9 of the table top panel 6 and the adjacent top face 5' of the edging frame which it is to cover, as indicated in Fig. 4. The peripheral edge portion of the covering sheet 20 as thus initially inserted into the groove 10 presents an inner side section 22 in hugging contact with the inner side face 11 of the groove, a bottom section 23 overlying the flat bottom face 13 of the groove, and an outer side section 24 in hugging contact with the outer side face 12 of the groove. The flattened side faces 31 of the rattan strip as thus pressure forced into the groove have sufficient roughness to firmly grip the smooth inside faces of the inner and outer side sections 22 and 24 of the covering sheet 20 which then line the side faces 11 and 12 of the groove.

When the rattan strip 30 has been pressure forced into the groove 10 as indicated in Fig. 4, the trimming spline 35 may be driven into the groove as indicated in Fig. 5. This may be accomplished by the use of a pressure roller which is rolled over the spline and exerts sufficient downward pressure to wedge the spline 35 into the groove with the side faces 35 of the spline in pressure contact with inner faces of the inner and outer side sections 22 and 24 of the covering sheet which line the side faces 11 and 12 of the groove. A rubber hammer may be used to finish driving the trimming spline 35 into the groove, the flat bottom face 37 of the spline 35 being pressed against the rattan strip 30 to flatten the top face 38 thereof, and also flatten the bottom face 32 thereof, so that the rattan strip 30 becomes reshaped from its original round cross section as shown in Fig. 3 into its final rectangular cross section as indicated in Fig. 6.

As thus finally flattened and reshaped, the rattan strip 30 presents flat side faces 31 which grip the inner and outer side sections 22 and 24 of the covering sheet, a flat bottom face 32 which seats flatly against and frictionally engages the flattened bottom section 23 of the covering sheet, and a flat top face 38 against which the bottom face 37 of the trimming spline 35 is pressed. The rattan strip 30 as finally forced into the groove 10 also presents substantially square bottom corners 34 which flatten the bottom section 23 of the covering sheet and provides the bottom section 23 with substantially square bottom folds 27 which are wedged into the bottom corners 16 of the groove 10 and in shaped conformity therewith.

While the trimming spline 35 may be employed to effect final flattening of the bottom face 32

and the top face 33 of the rattan strip 30 as indicated in Figs. 5 and 6, it is preferable to effect final rectangular shaping of the rattan strip 30 before the trimming spline is inserted, as indicated in Fig. 7. Final rectangular shaping and flattening of the bottom face 32 and top face 33 of the rattan strip 30 may be effected by using a flat rimmed roller loaded with ample pressure to flatten the bottom section 23 of the covering sheet firmly against the bottom face 13 of the groove, and to wedge the corner folds 27 thereof into the bottom corners 16 of the groove in tight shape conformity therewith. As thus pressure flattened, the rattan strip will permanently retain its rectangular shape with the bottom section 23 and the side sections 22 and 24 of the covering sheet tenaciously gripped between the roughened bottom face 13 and side faces 14 and 15 of the groove 10 and the rough and flattened bottom face 32 and the rough and flattened side faces 34 of the rattan strip 30.

The trimming spline 35 may then be pressure wedged in superimposed relation over the roller flattened rattan strip 30, with the side faces 26 of the spline 35 firmly pressed against the side sections 22 and 24 of the covering sheet, following which the terminus end portion 25 may be cut off at 26 as shown in Fig. 6.

As an alternative procedure, the outer side section 24 of the covering sheet 20 may be cut off at 28' as shown in Fig. 8 and the end section 24' thereof folded to overlie the flattened top face 33 of the rattan strip before the trimming spline is inserted. A trimming spline 35' is then selected which is slightly thicker than the trimming spline 35 shown in Figs. 5 and 6, so that one face 36 thereof will press against the inner side section 22 of the covering sheet 20 and the other face 36' thereof will be wedged directly against the roughened outer face 12 of the groove 10 as shown in Fig. 9. The trimming spline 35' may be wedged into the groove by a suitable pressure roller, and as finally driven in the groove the bottom face 37 of the spline 35' will snugly seat against the underlying end section 24' of the covering sheet as shown in Fig. 10. Since the outer side face 36' of the spline 35' is in tight frictional engagement with the roughened outer side face 12 of the groove, the spline 35' is securely locked in the groove, with the end section 24' of the covering sheet wedged between the bottom face 37 of the spline and the roughened upper face 33 of the rattan strip 30.

It has been the present practice to select a trimming spline 35a as shown in Fig. 11 of the maximum thickness permissible, and when the trimming spline 35a is driven into the groove, it is intended that the peripheral edge portion of the covering sheet be thereby also driven into the groove. However, since the trimming spline 35a is hard and unyielding the inner and outer corner folds 26a and 29a of the covering sheet have a tendency to bind against the relatively sharp inner and outer corners 14 and 15 of the groove. This undesired corner binding action prevents the center section 21 of the covering sheet from being drawn taut and smooth as the trimming spline 35a is driven into the groove, leaving the center section 21 loose and wrinkled. Further, when the bottom section 23a of the covering sheet is driven into the groove by the driving pressure exerted on the spline 35a, the side sections 22a and 24a and the bottom section 23a of the covering sheet will be substan-

5 tially stretched and deformed as indicated in Fig. 12.

Thus as exemplified in Figs. 11 and 12, the previous practice of attempting to secure the peripheral edge portion of the covering sheet in the frame groove by means of the trimming spline has serious deficiencies since the unyielding spline causes the inner and outer folds 26a and 29a of the covering sheet to bind against the inner and outer corners 14 and 15 of the groove, thereby preventing the center section 21 of the covering sheet from being drawn taut and smooth over the table top, and additionally places the side sections 22a and 24a and the bottom sections 23a of the covering sheet under substantial stretch. As thus stretched, the side sections 22a and 24a and the bottom sections 23a of the covering sheet exert upward pushing pressure on the trimming spline 35a driven into the groove, and since the faces of the covering sheet in contact with the spline are relatively smooth and glossy, there is a constant tendency for the spline to creep out of the groove under the varying temperature and humidity conditions to which the table top is subjected during storage, shipment and use.

30 By driving the peripheral edge portion of the covering sheet into the groove by the use of an initially substantially round rattan strip 30 as shown in Fig. 4, the peripheral edge portion of the covering sheet is free to ride over the inner and outer corners 14 and 15 in the groove in a manner so that the center section 21 of the covering sheet is drawn taut over the table top without imposing a deforming stretch on either the center section 21, the side sections 22 and 24, or the bottom section 23 of the covering sheet. When the rattan strip 30 is then reshaped into rectangular form by roller pressure applied thereto, the squared side faces 31 and the squared bottom face 32 of the rattan strip will frictionally grip the glossy surface of the side sections 22 and 24 and the bottom section 23 of the covering sheet without substantial stretch deformation thereof, and in a manner to immovably retain the peripheral edge portion thereof permanently locked in fixed position within the groove 10, so that neither temperature nor humidity changes, nor normal use over long periods of time, will loosen the covering sheet as thus applied to the table top.

As thus constructed, the center section 21 of the covering sheet remains permanently taut and smoothly hugs the top face 9 of the table top panel 6 with the inner corner fold 26 of the covering sheet snugly folded over the upper inner corner 14 of the groove. When the trimming spline is driven into final position within the groove, its slightly arcuate outer face 33 is at an elevation between the top face 5 of the edging frame 2 and the smooth outer face of the center section 21 of the covering sheet.

60 In the embodiment shown in Figs. 7 to 10 inclusive, the end section 24' of the covering sheet 20 is wedged between the lower face 37 of the spline 35' and the rough and flat top face 33 of the rattan strip 30, so that the peripheral edge portion of the covering sheet cannot creep or slip, and since one face 36' of the spline 35' is frictionally gripped by the roughened side face 12 of the groove 10, immovability to the trimming spline as finally wedged into the groove is further assured. Further, since the peripheral edge portion of the covering sheet as pressed into the groove by the rattan strip 30 is under no appreciable tensile stretch, the groove inserted

portion of the covering sheet exerts little or no upward lifting pressure on either the rattan strip 30 or the trimming spline inserted into the groove.

The employment of rattan strips 30 over which the trimming splines 35 are superimposed have been found to solve the serious problem of loosening and creeping of the covering sheets as previously secured to table tops. The use of this improved securing means for permanently and immovably locking the peripheral edge portion of the covering sheet to the table top does not add appreciably to the manufacturing cost of sheet covered table tops as heretofore manufactured, and yet insures substantial permanence to the construction under varying temperature and humidity conditions.

While certain novel features of the invention have been disclosed herein, and are pointed out in the claims, it will be understood that various omissions, substitutions, and changes may be made by those skilled in the art without departing from the spirit of this invention.

What is claimed is:

1. In combination with a covered table top presenting a wood edging frame having a finished upper face, a table top panel fitted within said edging frame, and a covering sheet extending over said table top panel, of means for securing the peripheral edge portion of said covering sheet to said edging frame, said securing means including a groove formed in the upper finished face of the edging frame into which the peripheral edge portion of the covering sheet is inserted, a deformable rattan strip of initially oversize and substantially circular cross-sectional contour pressure driven into said groove and pressure flattened into tight fitting overlying relationship to the inserted peripheral edge portion of the covering sheet, and a trimming spline pressure wedged into the groove in superimposed relationship over the rattan strip.

2. In combination with a covered table top presenting an edging frame having a finished upper face, a table top panel fitted within said edging frame, and a covering sheet extending over said table top panel, of means for securing the peripheral edge portion of said covering sheet to said edging frame, said securing means including a groove formed in the upper finished face of the edging frame into which the peripheral edge portion of the covering sheet is inserted, said groove presenting roughened but substantially parallel extending side faces and a roughened but substantially flat bottom face, an oversize rattan strip initially of generally circular cross-sectional contour pressure driven into said groove and pressure flattened into tight fitting overlying relationship to the inserted peripheral edge portion of the covering sheet, and a trimming spline pressure wedged into the groove in superimposed relationship over the rattan strip.

3. In combination with a covered table top presenting an edging frame having a finished upper face, a table top panel fitted within said edging frame, and a covering sheet extending over said table top panel, of means for securing the peripheral edge portion of said covering sheet to said edging frame, said securing means including a groove formed in the upper finished face of the edging frame into which the peripheral edge portion of the covering sheet is inserted, an oversize rattan strip initially of generally circular cross-sectional contour pressure

driven into said groove in overlying relationship to the inserted peripheral edge portion of the covering sheet, said inserted rattan strip being pressure flattened to substantially rectangular contour, with the inner and outer side sections of the groove-inserted edge portion of the covering sheet compressed and wedged between the adjacent side faces of the groove and the adjacent flattened side faces of the rattan strip, and with the bottom section of the groove inserted edge portion of the covering sheet compressed and wedged between the bottom face of the groove and the flattened bottom face of the rattan strip, and a trimming spline pressure wedged into the groove in superimposed relationship over the flattened rattan strip.

4. In combination with a covered table top presenting an edging frame having a finished upper face, and a table top panel fitted within said edging frame, a covering sheet extending over said table top panel, of means for securing the peripheral edge portion of said covering sheet to said edging frame, said securing means including a groove formed in the upper finished face of the edging frame into which the peripheral edge portion of the covering sheet is inserted, said groove presenting roughened but substantially parallel extending side faces and a roughened but substantially flat bottom face, an oversize rattan strip initially of generally circular cross-sectional contour pressure driven into said groove and pressure flattened into tight fitting overlying relationship to the inserted peripheral edge portion of the covering sheet, and a trimming spline pressure wedged into the groove in superimposed relationship over the rattan strip, one side face of said spline being in pressure contact against the adjacent side section of the groove inserted edge portion of the covering sheet, and the other side of said spline being in pressure contact with the adjacent roughened side face of said groove.

5. In combination with a covered table top presenting an edging frame having a finished upper face, a table top panel fitted within said edging frame, and a covering sheet extending over said table top panel, of means for securing the peripheral edge portion of said covering sheet to said edging frame, said securing means including a groove formed in the upper finished face of the edging frame into which the peripheral edge portion of the covering sheet is inserted, an oversize rattan strip initially of generally circular cross-sectional contour driven into said groove in overlying relationship to the inserted peripheral edge portion of the covering sheet, said inserted rattan strip being pressure flattened to substantially rectangular contour with the inner and outer side sections of the groove-inserted edge portion of the covering sheet compressed and wedged between the adjacent side faces of the groove and the adjacent flattened side faces of the rattan strip and with the bottom section of the groove inserted edge portion of the covering sheet compressed and wedged between the bottom face of the groove and the flattened bottom face of the rattan strip, said groove inserted edge portion of the covering sheet having the end section thereof folded over the upper part of the rattan strip, and a trimming spline pressure wedged into the flattened rattan strip and with the bottom face thereof seating against the end section of the covering sheet.

11

6. In combination with a covered table top presenting an edging frame having a finished upper face, a table top panel fitted within said edging frame, and a covering sheet extending over said table top panel, of means for securing the peripheral edge portion of said covering sheet to said edging frame, said securing means including a groove formed in the upper finished face of the edging frame into which the peripheral edge portion of the covering sheet is inserted, said groove presenting roughened but substantially flat parallel side faces and a roughened but substantially flat bottom face, an oversize rattan strip initially of generally circular cross-sectional contour driven into said groove in overlying relationship to the inserted peripheral edge portion of the covering sheet, said inserted rattan strip being pressure flattened to substantially rectangular contour, with the inner and outer side sections of the groove-
20 inserted edge portion of the covering sheet compressed and wedged between the adjacent side faces of the groove and the adjacent flattened side faces of the rattan strip and with the bottom section of the groove-inserted edge portion of
25 the covering sheet flattened and compressed between the flat bottom face of the groove and
